Patented Jan. 15, 1918.

UNITED STATES PATENT OFFICE.

KIYATARO KANSAKA, OF PASADENA, CALIFORNIA.

VEHICLE-TOP.

1,253,835.

Specification of Letters Patent. Patented Jan. 15, 1918.

Application filed November 4, 1916. Serial No. 129,526.

To all whom it may concern:

Be it known that I, KIYATARO KANSAKA, a citizen of Japan, residing at Pasadena, in the county of Los Angeles and State of California, have invented certain new and useful Improvements in Vehicle-Tops, of which the following is a specification.

The invention relates to collapsible tops for vehicles, and the objects of my invention are, first, to obtain a construction that may be readily handled by one person in adjusting it from collapsed to extended position, or the reverse; and, second, to secure the above object by the use of a single rear bow disposed in such a manner as not to come within the ordinary field of vision of the occupants of the vehicle.

I attain the desired objects by the construction illustrated in the accompanying drawing, showing one embodiment of the invention, in which—

Figure 1 is a side elevation of the top in extended position, the method for attaching it to a vehicle and its relation thereto being indicated; Fig. 2 is a side elevation of the top in collapsed position and drawn to a larger scale than Fig. 1; Fig. 3 is a fragmentary sectional detail to a still larger scale, taken on the line 3—3 of Fig. 1, and looking in the direction indicated by the arrows; and Fig. 4 is a detail on a large scale of the bolt and nut used for attaching certain of the parts together.

Similar numbers refer to similar parts throughout the several views.

The main supporting bow 1 has its two arms pivotally secured to the sides of the vehicle at 2, in such a manner that it extends upwardly and rearwardly when the top is in extended position, and rearwardly in substantial horizontal position when the top is collapsed.

Attached to bow 1, at each side, are lazy-tong frames comprising a series of links extending forwardly in substantially horizontal position when the top is extended, and arranged to fold substantially parallel to the bow and in close proximity thereto, when the top is collapsed. The rear ends of links 3 of the lazy-tong frame are pivotally attached to bow 1, near its upper part at each side, as shown at 4. This attachment is most conveniently made by means of the fitting 5, secured to the bow. The rear end 55 of the co-operating links 6 are arranged to

engage the slots 7, in the slotted members 8 attached to the two sides of bow 1, so as to be capable of moving slidably as well as pivotally with reference to the slots. For this purpose the head 9 of bolt 10 is passed 60 through the opening 11 in the slotted member. The link 6 is then mounted upon the bolt, and by means of the nut 12 is firmly tightened against shoulder 13, suitable washers 14 being used if desired to give the 65 proper spacing, and to reduce any tendency that the nut may have to work loose.

Links 3 and 6 are pivotally connected together at their centers, as shown at 15 and their forward ends are pivotally connected 70 to links 16 and 17 respectively. These in turn are pivotally connected together at their centers at 18, and their forward ends are pivotally connected to links 19 and 20 respectively. The latter two links are also 75 pivotally connected at their centers at 21.

Link 22 is preferably bent at an angle as shown, although the same result may be secured by means of an off-set lug made integral with it. It is pivotally connected at 80 one end with link 20, and at its center with the short link 23 at 24. Links 19 and 23 are pivotally connected at 25.

The links 17, 20, and 23 are attached respectively to the cross bows 26, 27, and 28, 85 serving to support the canopy indicated by the dotted line. The link 22 is attached at its forward end to the cross bow 29, supporting the front portion of the canopy and by means of which the latter is stretched 90 tight when the frame is in extended position.

There is a suitable fitting 30 attached to the under part of cross bow 29 at either side, for securing the forward ends of the lazy-tong frames to the wind shield standards of the vehicle, or other convenient supporting means. The weight of the canopy, and its supporting frame, is supported at the forward end by these means, and at the rear the weight is carried by pivot 2 acting 100 through the main supporting bow 1.

The links 3, 17, and 20 are provided with short projecting lugs or pins 31, 32, and 33 respectively. These serve to limit the amount of extension of the lazy-tong frames, 105 and to make them rigid in extended position so as to be capable of supporting the weight imposed upon them. The links 6, 16, and 19 are provided with recesses 34, 35, and 36 respectively, registering with the aforesaid 110

lugs when the frame is collapsed so that the latter may be closely folded into the position shown in Fig. 2.

To permit of the collapsing of the frame 5 the fitting 30 is first unfastened from its support. The front part of the frame may then be pushed rearwardly until the links are all substantially parallel and in close proximity to the rear supporting bow 1. During this 10 process the latter will have taken a substantially horizontal position as shown in Fig. 2, and the rear end of link 6 will have moved downwardly and forwardly to the other end of slot 7.

15 An especially important feature of my invention is the lack of supporting and bracing members in the ordinary field of vision of the occupants of a vehicle with which it is equipped. The rear supporting bow 1 extends backwardly so that ordinarily its 20 upper portions are in the rear of a person sitting in the back seat. At the forward end the supporting means already exist in the great majority of cases, and otherwise they 25 may be made of small dimensions, and sightly in appearance.

Having thus fully described my invention, I claim:

1. In a vehicle top frame comprising a 30 rear bow adapted for pivotal connection to a vehicle body, the combination of lazy-tong structures attached to said bow at each side and adapted to extend forwardly therefrom, with intermediate bows supported by 35 extensions of the links of said structures; one link of each crossed pair of said structures

being provided with a projecting pin to limit its movement in extension, the other links of said pairs having notches to permit said structures to be compactly collapsed by 40 registering with said pins.

2. In a vehicle top frame comprising a rear bow adapted to be pivoted to a vehicle body, the combination of lazy-tong structures attached to said bow and adapted to 45 extend forwardly therefrom, with intermediate bows supported by the links of said structures; said links being arranged in crossed pairs having projecting pins to limit their movement in extension and notches to 50 permit said structures to be compactly collapsed by registering with said pins.

3. In a vehicle top frame comprising a rear bow, the combination of lazy-tong structures attached thereto and forwardly 55 extensible therefrom, with intermediate bows supported by said structures; the links of said structures being provided with projecting pins to limit their movement in extension and notches to permit said structures 60 to be compactly collapsed by registering with said pins.

4. In a vehicle top frame comprising a rear bow and lazy-tong structures forwardly extensible therefrom, projecting pins attached 65 to the links of said structures to limit their movement in extension, and notches formed in the cooperating links to permit said structures to be compactly collapsed by registering with said pins.

KIYATARO KANSAKA.
